(57) **CLAIM**

We claim the ornamental design for an earphone, as shown and described.

DESCRIPTION

FIG. 1 is a front side perspective view of an earphone; FIG. 2 is a rear side perspective view of the earphone; FIG. 3 is a front elevational view of the earphone; FIG. 4 is a rear elevational view of the earphone; FIG. 5 is a top plan view of the earphone; FIG. 6 is a bottom plan view of the earphone; FIG. 7 is a left side elevational view of the earphone; and, FIG. 8 is a right side elevational view of the earphone. Portions of the drawings shown in broken lines form no part of the claimed design. The dot dash line represents a boundary of the claim and forms no part thereof.

1 Claim, 8 Drawing Sheets(56)
